United States Patent

Des. 236,959
Patented Sept. 30, 1975

236,959

LEVEL INSTRUMENT

Donald E. Wright, 14265 Juneau Blvd.,
Elm Grove, Wis. 53122

Filed May 24, 1974, Ser. No. 473,075

Term of patent 14 years

Int. Cl. D10—05

U.S. Cl. D10—69

FIG. 1 is a perspective view of a level instrument showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left end elevational view thereof;

FIG. 7 is a right end elevational view thereof;

FIG. 8 is a partial plan view of FIG. 5 with parts broken away; and

FIG. 9 is a sectional view of FIG. 8 taken along lines 9-9 thereof.

I claim:

The ornamental design for a level instrument, as shown and described.
